UNITED STATES PATENT OFFICE.

RICHMOND E. MALLORY, OF WEST SALEM, OHIO.

EAVES-TROUGH HANGER.

SPECIFICATION forming part of Letters Patent No. 258,453, dated May 23, 1882.

Application filed March 25, 1882. (No model.)

To all whom it may concern:

Be it known that I, RICHMOND E. MALLORY, a citizen of the United States, and resident at West Salem, in the county of Wayne and State 5 of Ohio, have invented a new and valuable Improvement in Eaves-Trough Hangers; and I do hereby declare that the following is a full, clear, and exact description of the construction and operation of the same, reference being had 10 to the annexed drawings, making a part of this specification, and to the letters and figures of reference marked thereon.

Figure 1 of the drawings is a representation of a side view of my improved eaves-trough hanger. Fig. 2 is a top or plan view of the 15 same.

This invention has relation to hangers for eaves-troughs; and it consists in the construction and novel arrangement of the supporting-strap, its perforated arm and perforated 20 catch-lip, and the pivoted latch-bar having a curved end surmounted by a stud to engage the perforation of the catch-lip, the engagement being secured by the elasticity of the 25 strap, all as hereinafter set forth.

In the accompanying drawings, the letter A designates the curved bearing portion of the supporting strap or hanger B. The outer end of the curved bearing A is formed with a curved 30 extension or catch-lip, C, the end of which overhangs and is perforated at d. From the opposite end of the curved bearing A extends the horizontal portion E of the angular supporting-arm B. This horizontal portion E extends toward the catch-lip C for about half the 35 breadth of the trough, which is seated in the

bearing A, and it is perforated at g for the rivet h, whereby the latch-bar K is pivoted to this part of the hanger. The latch-bar K extends transversely over the trough, and its outer end, l, is upwardly and outwardly curved 40 to fit neatly under the curved catch-lip C of the main strap. On the upper surface of the curved end l is a stud, s, which, when the latch-bar is brought under the catch-lip, engages the perforation d of the latter, and thereby locks it against lateral displacement, and at the same time fastens the curved bearing A and the latch-bar K together in such a manner that spreading of the curved bearing will 45 be prevented. The latch-bar should be so pivoted to the horizontal portion E of the hanger-arm that when sprung under the catch-lip a forcible engagement will be effected between the stud of the latch-bar and the perforation 50 of the catch-lip.

Having described this invention, what I claim, and desire to secure by Letters Patent, is—

The eaves-trough hanger consisting of the supporting strap B, its perforated arm E and 60 perforated catch-lip C, and the pivoted latch-bar K, its curved end l fitting under the catch-lip and its stud s engaging the perforation d of said catch-lip, substantially as specified.

In testimony that I claim the above I have 65 hereunto subscribed my name in the presence of two witnesses.

RICHMOND EUGENE MALLORY.
